ABSTRACT OF THE DISCLOSURE

This invention concerns pyrrolo[1,2,3-*de*]quinoxalin-2(3H)-ones and related compounds which are pharmaco logically active as central nervous system depressants.

This application is a division of our prior, copending application, Ser. No. 831,723, filed June 9, 1969 now abandoned.

This invention relates to new and novel quinoxalines. More particularly it relates to pyrrolo[1,2,3-*de*]quinoxalin-2(3H)-ones and related compounds which in standard and accepted biological tests have demonstrated usefulness as central nervous system depressants.

The new and novel compounds of the present invention are exemplified by those having the formula:

wherein R₁ and R₂ are selected from the group consisting of hydrogen, nitro, amino, carboxy, cyano, carbamyl, sulfamyl, trifluoromethyl, halogen, lower alkyl, lower alkoxy, lower alkylthio, carb(lower)alkoxy, lower alkylsulfonyl, carboxy(lower)alkyl, lower alkanoylamino, di(lower) alkanoylamino, phenyl, halophenyl, lower alkylphenyl, lower alkoxyphenyl, phen(lower)alkyl, phen(lower)alkoxy, morpholino, pyridyl, furyl, and naphthyl; R₃ and R₄ when taken separately are selected from the group consisting of hydrogen, cyano, carboxy, carbamyl, lower alkyl, hydroxy(lower)alkyl, carb(lower)alkoxy, carb(lower)alkoxy(lower)alkyl, carboxy(lower)alkyl, di(lower)alkylamino(lower)alkyl, phenyl, hydroxyphenyl, lower alkylphenyl, lower alkoxyphenyl, halophenyl, phen(lower)alkyl, benzoxyphenyl, pyridyl, furyl, and naphthyl; R₃ and R₄ when concatenated and taken together with the two carbon atoms to which they are attached complete a ring selected from the group consisting of 1-(lower) alkyl - 1,2,5,6 - tetrahydro - 3,4 - pyridindiyi, 4,5 - dihydro - (H - benzocyclohepten - 1,2 - ylene, 1 - cycloalken-1,2 - ylene containing from about 5 to about 12 carbon atoms, 1 - (lower)alkyl - 1 - cyclohexen - 1,2 - ylene and 3,4 - dihydro - 1,2 - naphthylene; and R₅ is selected from the group consisting of hydrogen, lower alkyl, cyano(lower)alkyl, phen(lower)alkyl, morpholino(lower)alkyl, lower alkanoylamino(lower)alkyl, di(lower)alkylamino(lower)alkyl, N - (lower)alkyl - N' - (lower)alkanoylamino(lower)alkyl, aziridinyl(lower)alkyl, azetidinyl(lower)alkyl, azolidinyl(lower)alkyl, azinyl(lower)alkyl, azepinyl(lower)alkyl, 1 - (lower)alkylpiperazinyl(lower)alkyl, 1 - phenylpiperazinyl(lower)alkyl, 1 - halophenylpiperazinyl(lower)alkyl and 1 - phen(lower)alkylpiperazinyl(lower)alkyl. As employed herein the terms "lower alkyl,"

"lower alkoxy," "lower alkanoyl" and the like are meant to include both branched and straight chain hydrocarbon groups having from one to about seven carbon atoms. The term "halogen" as used herein is meant to include chlorine, bromine, iodine and fluorine. Typical examples of these compounds are:

- 7,8,9,10-tetrahydro-8-methyl-1H-pyrrolo[3',4':4,5]pyrrolo[1,2,3-*de*]quinoxalin-2(3H)-one;
 8,9-dihydro-1H,7-benzo[3',4']cyclohepta[1',2':4,5]pyrrolo[1,2,3-*de*]quinoxalin-2(3H)-one;
 8,9,10,11-tetrahydro-1H,7H-cyclohepta[4,5]pyrrolo[1,2,3-*de*]quinoxalin-2(3H)-one;
 7,8,9,10,11,12-hexahydro-1H-cycloocta[4,5]pyrrolo[1,2,3-*de*]quinoxalin-2(3H)-one;
 8-*tert*-butyl-7,8,9,10-tetrahydro-1H-pyrazino[3,2,1-*jk*]carbazol-2(3H)-one;
 2,3-dihydro-2-oxo-5-phenyl-1H-pyrrolo[1,2,3-*de*]quinoxaline-6-acetic acid;
 8,9,10,11-tetrahydro-3-methyl-1H,7H-cyclohepta[4,5]pyrrolo[1,2,3-*de*]quinoxalin-2(3H)-one;
 3-(2-dimethylaminoethyl)-8,9,10,11-tetrahydro-1H,7H-cyclohepta[4,5]pyrrolo[1,2,3-*de*]quinoxalin-2(3H)-one;
 2,3,8,9,10,11-hexahydro-2-oxo-1H,7H-cyclohepta[4,5]pyrrolo[1,2,3-*de*]quinoxaline-3-acetonitrile;
 8,9,10,11-tetrahydro-3-phenethyl-1H,7H-cyclohepta[4,5]pyrrolo[1,2,3-*de*]quinoxalin-2(3H)-one;
 6-methyl-1-(2-dimethylaminoethyl)-5-phenyl-1H-pyrrolo[1,2,3-*de*]quinoxalin-2(3H)-one; and
 1-(3-dimethylaminopropyl)-5-methyl-6-phenyl-1H-pyrrolo[1,2,3-*de*]quinoxalin-2(3H)-one.

The new and novel compounds of the present invention may be prepared by the process which is exemplified by the following reaction scheme:

wherein R₁, R₂, R₃, R₄ and R₅ are defined as above and X is a halogen. The reduction-cyclization reaction is effected by contacting a 1-nitroso-3,4-dihydroquinoxalin-2(1H)-one (I) with zinc dust in acetic acid for about one-half hour at about ambient temperatures. Thereafter, the reduced mixture is contacted with an appropriate ketone (II) at about reflux temperatures for a period of up to about thirty minutes to afford an appropriate 1-unsubstituted product (III). Preferably this reaction is conducted in glacial acetic acid. When the reduction-cycliza-

tion reaction is complete, the 1-unsubstituted product (III) is separated by conventional recovery procedures e.g. filter the reaction mixture, wash the cake with acetic acid and a liquid alkanol and crystallize the 1-unsubstituted product (III) from a suitable solvent, such as, dimethylformamide or dimethylacetamide.

The alkylation reaction is effected by admixing the above-prepared 1-unsubstituted product (III) with hexane washed fifty percent sodium hydride, in an anhydrous, reaction-inert solvent, e.g. dimethylformamide. To this mixture, there is added a solution of an appropriate halide (IV) in an anhydrous, reaction-inert solvent, e.g. dimethylformamide at a temperature range from about 70° C. to about 90° C. for a period of up to about two hours. When the alkylation is complete, the resulting 1-substituted product (V) is recovered by standard techniques. For example, the solvent is evaporated to afford a residue which is purified and then crystallized from a suitable solvent, e.g. an alkanol.

The 1-nitroso-3,4-dihydroquinoxalin-2(1H)-ones (I) employed as starting materials in the above-described process are prepared by the procedure of Perkin, W. H. and Riley, G. C. in J. Chem. Soc., 2399 (1923). The ketones (II) and halides (IV) employed in these reactions are commercially available or are easily prepared by processes well known in the chemical art.

The new and novel 1-unsubstituted (III) and 1-substituted (V) products of this invention possess valuable pharmacological activity. In particular, these compounds in standard pharmacological procedures demonstrate nervous system activity and are useful as depressants. Because of this property they are of particular importance in producing a calming effect in animals.

In the pharmacological evaluation of the central nervous system depressant compounds of this invention the *in vivo* effects of the compounds of this invention are tested as follows:

The compound is administered orally and intraperitoneally to three mice (14 to 24 grams) at each of the following doses: 400, 127, 40 and 12.7 mg./kg. The animals are watched for a minimum of two hours during which time signs of general stimulation (i.e., increased spontaneous motor activity, hyperactivity on tactile stimulation, twitching), general depression (i.e., decreased spontaneous motor activity, decreased respiration) and autonomic activity (i.e., miosis, mydriasis, diarrhea) are noted. The animals are tested for changes in reflexes (i.e., flexor, extensor) and are rated by use of a pole climb and inclined screen for the presence of sedation-ataxia. The "Eddy Hot-Plate Method" [Nathan B. Eddy and Dorothy Leimbach, J. Pharmacol. Exper. Therap. 107, 385 (1953)] is used to test for analgesia. The experiment is terminated by subjecting each animal to a maximal electroshock to test for anti-convulsant activity.

The compounds of this invention in the above test procedure induce decreased motor activity and decreased respiration when administered at a dosage range of 12.7 to 400 mg./kg. There were no deaths in the test animals at the highest dose used, 400 mg./kg. orally and intraperitoneally.

The 1-unsubstituted products (III) of the present invention are also useful intermediates in the preparation of the corresponding 1-substituted products (V) hereof. Further, when tested by the procedure set forth in the Cancer Chemotherapy Reports Number 25, the following 1-substituted products (V) of the present invention have demonstrated activity as anti-tumor agents when administered to rats at an intraperitoneal dosage range from about 62.5 to about 175 mg./kilo of body weight:

1-(3-dimethylaminopropyl)-6-ethyl-5-phenyl-1H-pyrrolo[1,2,3-de]quinoxalin-2(3H)-one;
1-(3-dimethylamino-2-methylpropyl)-6-ethyl-5-phenyl-1H-pyrrolo[1,2,3-de]quinoxalin-2(3H)-one;

- 1-(2-dimethylaminoethyl)-6-ethyl-5-phenyl-1H-pyrrolo[1,2,3-de]quinoxalin-2(3H)-one;
1-(2-dimethylaminoethyl)-6-ethyl-5-phenyl-1H-pyrrolo[1,2,3-de]quinoxalin-2(3H)-one;
5 6-ethyl-5-phenyl-1-[3-(1-pyrrolidinyl)-propyl]-1H-pyrrolo[1,2,3-de]quinoxalin-2(3H)-one;
1-(3-dimethylaminopropyl)-5-(*p*-methoxyphenyl)-6-methyl-1H-pyrrolo[1,2,3-de]quinoxalin-2(3H)-one;
10 5-(*p*-benzyloxyphenyl)-1-(3-dimethylaminopropyl)-6-methyl-1H-pyrrolo[1,2,3-de]quinoxalin-2(3H)-one;
1-(3-dimethylaminopropyl)-5-(*p*-hydroxyphenyl)-6-methyl-1H-pyrrolo[1,2,3-de]quinoxalin-2(3H)-one;
6-methyl-1-(2-dimethylaminoethyl)-5-phenyl-1H-pyrrolo[1,2,3-de]quinoxalin-2(3H)-one;
15 3-(2-dimethylaminoethyl)-7,8,9,10,11,12-hexahydro-1H-cycloocta[4,5]pyrrolo[1,2,3-de]quinoxalin-2(3H)-one;
5-benzyl-1-(2-dimethylaminoethyl)-6-phenyl-1H-pyrrolo[1,2,3-de]quinoxalin-2(3H)-one; and
20 1-(2-dimethylaminoethyl)-6-ethyl-5-phenyl-1H-pyrrolo[1,2,3-de]quinoxalin-2(3H)-one.

Still further, some of the 1-substituted products (V) of the present invention have also demonstrated immunosuppressive activity by their ability to inhibit experimentally induced allergic encephalomyelitis in rats when administered at an intraperitoneal dosage range of about 100 to about 200 mg./kilo of body weight. This immunosuppressive activity was tested by procedures of Brandiss, M. W. Science 140:186, 1963 and Levine *et al.* Proc. Soc. 25 114:220, 1963. The compounds which have demonstrated this activity are: 1-(3-dimethylaminopropyl)-6-ethyl-5-phenyl-1H-pyrrolo[1,2,3-de]quinoxalin-2(3H)-one; 1-(2-dimethylaminoethyl)-6-ethyl-5-phenyl-1H-pyrrolo[1,2,3-de]quinoxalin-2(3H)-one; and 1-(3-dimethylaminopropyl)-5-(*p*-hydroxyphenyl)-6-methyl-1H-pyrrolo[1,2,3-de]quinoxalin-2(3H)-one.

When the compounds (III and V) of this invention are employed as central nervous system depressants they may be administered to warm-blooded animals, e.g. mice, rats, rabbits, dogs, cats, monkeys, etc. alone or in combination with pharmacologically acceptable carriers, the proportion of which is determined by the solubility and chemical nature of the compound, chosen route of administration and standard biological practice. For example, they may be administered orally in the solid form containing such excipients as starch, milk sugar, certain types of clay and so forth. They may also be administered orally in the form of solutions or they may be injected parenterally. For parenteral administration they may be used in the form of a sterile solution containing other solutes, for example, enough saline or glucose to make the solution isotonic.

55 The dosage of the present central nervous system depressants will vary with the form of administration and the particular compound chosen. Furthermore, it will vary with the particular subject under treatment. Generally, treatment is initiated with small dosages substantially less than the optimum dose of the compound. Thereafter, the dosage is increased by small increments until the optimum effect under the circumstances is reached. In general, the compounds of this invention are most desirably administered at a concentration level that will generally afford effective results without causing any harmful or deleterious side effects.

EXAMPLE I

- 1-nitroso - 3,4 - dihydroquinoxalin-2(1H)-one (20 g., 70 0.113 mole) is stirred in glacial acetic acid (300 ml.) and zinc dust (40 g.) is added in portions while keeping the temperature below 25° C. When all of the zinc has been added the mixture is stirred an additional twenty minutes. Then the reduction mixture is filtered into a one-liter 75 flask containing propiophenone (15.2 g., 0.113 mole), and

the zinc cake washed with acetic acid (100 ml.) before it dries. The solution is stirred and slowly heated to reflux until crystals form. If crystals form before reflux, the mixture is refluxed for ten minutes, cooled to 20° C. in ice, filtered and washed with acetic acid then ethanol, giving light yellow crystals (11.2 g., 36%), M.P. 285-288° C. (uncorr.) which crystallized from dimethylformamide, give white crystals of 6-methyl-5-phenyl-1H-pyrrolo[1,2,3-de]quinoxalin-2(3H)-one (10.7 g., 35%), M.P. 288-290° C. (uncorr.).

Analysis.—Calcd. for $C_{12}H_{14}N_2O$: C, 77.84; H, 5.38; N, 10.68. Found: C, 77.92; H, 5.31; N, 10.75.

EXAMPLE II

Repeating the procedure of Example I, to react 1-nitroso-3,4-dihydroquinoxalin-2(1H)-one with an appropriate hereinafter listed ketone, the following products are obtained:

Ketone	Product
N-methyl-4-piperidone	7,8,9,10-tetrahydro-8-methyl-1H-pyrrolo[3',4':5,6]quinoxalin-2(3H)-one, M.P. 265-267.5° C. (19% yield).
1-benzosuberone	8,9-dihydro-1H,7H-benzod[3',4']cyclohepta[1,2,3-de]quinoxalin-2(3H)-one, M.P. 295-297° C. (37% yield).
Cycloheptanone	8,9,10,11-tetrahydro-1H,7H-cyclohepta[4,5-pyrrolo[1,2,3-de]quinoxalin-2(3H)-one, M.P. 279-282° C. (44% yield).
Cyclooctanone	7,8,9,10,11,12-hexahydro-1H-cycloocta[4,5-pyrrolo[1,2,3-de]quinoxalin-2(3H)-one, M.P. 224-227° C. (31% yield).
4-t-butylycyclohexanone	8-t-butyl-7,8,9,10-tetrahydro-1H-pyrazino[3,2,1-jk]carbazol-2(3H)-one, M.P. 279-282° C. (38% yield).
3-benzoylpropionic acid	2,3-dihydro-2-oxo-5-phenyl-1H-pyrrolo[1,2,3-de]quinoxaline-6-acetic acid, M.P. 301-303° C. (decomp.), (16% yield).
cyclopentanone	8,9-dihydro-1H,7H-cyclopental[4,5-pyrrolo[1,2,3-de]quinoxalin-2(3H)-one, M.P. 283-285° C. (38% yield).
α-Tetralone	7,8-dihydro-1H-benzo[a]pyrazino[3,2,1-jk]carbazol-2(3H)-one, M.P. 309-311° C. (23% yield).
Butyrophenone	6-ethyl-5-phenyl-1H-pyrrolo[1,2,3-de]quinoxalin-2(3H)-one, M.P. 245-246° C. (54% yield).
Cyclododecanone	7,8,9,10,11,12,13,14,15,16-decahydro-1H-cyclo-dodeca[4,5-pyrrolo[1,2,3-de]quinoxalin-2(3H)-one, M.P. 247-249° C. (66% yield).
Phenyl-2-propanone	5-methyl-6-phenyl-1H-pyrrolo[1,2,3-de]quinoxalin-2(3H)-one, M.P. 282-284° C. (51% yield).
Ethylacetacetate	2,3-dihydro-5-methyl-2-oxo-1H-pyrrolo[1,2,3-de]quinoxaline-6-carboxylic acid, ethyl ester, M.P. 266.5-267.5° C. (15% yield).
Benzoylacetonitrile	2,3-dihydro-2-oxo-5-phenyl-1H-pyrrolo[1,2,3-de]quinoxaline-6-carbonitrile, M.P. 312-313° C. (30% yield).
4-hydroxy-4'-methoxybutyrophenone	6-(2-hydroxyethyl)-5-(p-methoxyphenyl)-1H-pyrrolo[2,3-de]quinoxalin-2(3H)-one, acetate, M.P. 199-201° C. (6% yield).
Do	6-(2-hydroxyethyl)-5-(p-methoxyphenyl)-1H-pyrrolo[1,2,3-de]quinoxalin-2(3H)-one, M.P. 231-233° C. (9% yield).
2-pentanone	6-ethyl-5-methyl-1H-pyrrolo[1,2,3-de]quinoxalin-2(3H)-one, M.P. 217-219° C. (38% yield).
Valerophenone	5-phenyl-6-propyl-1H-pyrrolo[1,2,3-de]quinoxalin-2(3H)-one, M.P. 230-230.5° C. (48% yield).
m-Chloropropiophenone	5-(m-chlorophenyl)-6-methyl-1H-pyrrolo[1,2,3-de]quinoxalin-2(3H)-one, M.P. 273-276° C. (60% yield).
o-Chloropropiophenone	5-(o-chlorophenyl)-6-methyl-1H-pyrrolo[1,2,3-de]quinoxalin-2(3H)-one, M.P. 219-222° C. (28% yield).
Levulinic acid	2,3-dihydro-5-methyl-2-oxo-1H-pyrrolo[1,2,3-de]quinoxaline-6-acetic acid, M.P. 236-237° C. (decomp.), (28% yield).
p-Benzoyloxypropiophenone	5-(p-benzoyloxyphenyl)-6-methyl-1H-pyrrolo[1,2,3-de]quinoxalin-2(3H)-one, M.P. 270-273° C. (52% yield).
p-Methoxypropiophenone	5-(p-methoxyphenyl)-6-methyl-1H-pyrrolo[1,2,3-de]quinoxalin-2(3H)-one, M.P. 278-281.5° C. (51% yield).
p-Chloropropiophenone	5-(p-chlorophenyl)-6-methyl-1H-pyrrolo[1,2,3-de]quinoxalin-2(3H)-one, M.P. 333-336° C. (57% yield).

EXAMPLE III

1-nitroso-3,4-dihydroquinoxalin-2(1H)-one (0.565 mole) is stirred in glacial acetic acid (1500 ml.) and zinc dust (200 g.) is added in portions while keeping the temperature below 25° C. When all of the zinc has been added, the mixture is stirred an additional half hour. Then the reaction mixture is filtered into a five liter flask containing 1,3-diphenylpropanone (0.565 mole), and the zinc

cake washed with acetic acid (500 ml.). The reaction solution is stirred and slowly heated to reflux until crystals form. If crystals form before reflux, the mixture is refluxed for ten minutes, cooled in ice, filtered and washed with acetic acid then ethanol, giving crystals of 5-benzyl-6-phenyl-1H-pyrrolo[1,2,3-de]quinoxalin-2(3H)-one, M.P. 240-242° C. (55% yield).

Analysis.—Calcd. for $C_{23}H_{18}N_2O$: C, 81.63; H, 5.36; N, 8.28. Found: C, 81.46; H, 5.34; N, 8.27.

EXAMPLE IV

When the procedure of Examples I-III is repeated to react a 1-nitroso-3,4-dihydroquinoxalin-2(1H)-one with an appropriate ketone, there is afforded compounds of the following formula:

25 wherein R_1 , R_2 , R_3 and R_4 are defined as follows:

R_1	R_2	R_3	R_4
Hydrogen	8-cyano	p -Tcyl	Propyl
8-chloro	9-chloro	Carboxy	p -Bromophenyl
8-trifluoromethyl	Hydrogen	Hydrogen	Carbomethoxy
7-ethoxy	8-amino	Carbamyl	p -Hydroxyphenyl
9-bromo	8-carboxy	p -Ethylphenyl	Hydrogen
8-ethyl	Hydrogen	Hydrogen	p -Methoxyphenyl
8-fluoro	9-sulfamyl	do	Butyryl
8-nitro	9-phenyl	p -Iodophenyl	Hydrogen
8-carbamyl	9-methylthio	Hydrogen	Valeryl
7-butyl	Hydrogen	do	Carbethoxy
8-ethylthio	9-ido	Phenpropyl	Hydrogen
8-methoxy	9-methoxy	Hydrogen	Dimethylaminoethyl
p -Chlorophenyl	Hydrogen	do	Hydrogen
8-morpholino	do	do	2-pyridyl
9-methyl	9-propoxy	do	2-naphthyl
sulfonyl			
Hydrogen	9-acetamido	do	Cyano
8-ethylsulfonyl	9-acetyl	do	m -fluorophenyl
7-carbomethoxy	8-benzyl	do	Naphthyl
8-dimethylamino	Hydrogen	do	2-furyl
8-pyridyl	9-butylthio	Dimethylaminopropyl	Hydrogen
Hydrogen	9-benzyloxy	Hydrogen	Do
8-carbethoxy	9-p-bromo	p -Butoxy	Do
7-propionyl	Hydrogen	Hydrogen	Phenethyl
8-phenethyl	do	do	Hydrogen
8-propionamido	do	do	Carbopropoxy

EXAMPLE V

1-nitroso-3,4-dihydroquinoxalin-2(1H)-one (0.226 mole) is stirred in glacial acetic acid (600 ml.) and zinc dust (80 g.) is added in portions while keeping the temperature below 25° C. When all of the zinc has been added, the mixture is stirred an additional half hour. Then the reduction mixture is filtered into a one liter flask containing N-ethyl-4-piperidone (0.226 mole), and the zinc cake washed with acetic acid (200 ml.). The reaction mixture is stirred and slowly heated to reflux for ten minutes. Thereafter, the mixture is cooled in ice, filtered and washed with acetic acid then methanol, to afford 8-ethyl-7,8,9,10-tetrahydro-1H-pyrrolo[3',4':5,6]pyrrolo[1,2,3-de]quinoxalin-2(3H)-one.

Similarly, when the following ketones are reacted with an appropriate 1-nitroso-3,4-dihydroquinoxalin-2(1H)-one, the following products are afforded:

Ketone	Product
N-propyl-4-piperidone	7,8,9,10-tetrahydro-8-propyl-1H-pyrrolo[3',4':5,6]pyrrolo[1,2,3-de]quinoxalin-2(3H)-one
1-methylpiperidone	7,8,9,10-tetrahydro-6,8-dimethyl-1H-pyrrolo[3',4':5,6]pyrrolo[1,2,3-de]quinoxalin-2(3H)-one
4-propylpiperidone	7,8,9,10-tetrahydro-8-propyl-1H-pyrrolo[3',4':5,6]pyrrolo[1,2,3-de]quinoxalin-2(3H)-one

EXAMPLE VI

When the procedure of the prior Examples are repeated to react a 1-nitroso - 3,4 - dihydroquinoxalin-2(1H)-one with an appropriate ketone, the following compounds are prepared:

- 6-(3-hydroxypropyl)-8-phenbutyl-1H-pyrrolo[1,2,3-de]quinoxalin-2(3H)-one propionate;
 8-benzyl-1H-pyrrolo[1,2,3-de]quinoxalin-2(3H)-one;
 8-(2-furyl)-1H-pyrrolo[1,2,3-de]quinoxalin-2(3H)-one;
 9-diethylamino-1H-pyrrolo[1,2,3-de]quinoxalin-2(3H)-one;
 8-(2-naphthyl)-1H-pyrrolo[1,2,3-de]quinoxalin-2(3H)-one;
 7-(m-butylphenyl)-1H-pyrrolo[1,2,3-de]quinoxalin-2(3H)-one;
 8-(p-methoxyphenyl)-1H-pyrrolo[1,2,3-de]quinoxalin-2(3H)-one;
 8-(p-propoxyphenyl)-1H-pyrrolo[1,2,3-de]quinoxalin-2(3H)-one;
 8-phenethoxy-1H-pyrrolo[1,2,3-de]quinoxalin-2(3H)-one;
 9-dipropylamino-1H-pyrrolo[1,2,3-de]quinoxalin-2(3H)-one;
 8-(p-fluorophenyl)-1H-pyrrolo[1,2,3-de]quinoxalin-2(3H)-one;
 8-(o-iodophenyl)-1H-pyrrolo[1,2,3-de]quinoxalin-2(3H)-one; and
 8-(N-methyl-N'-propylamino)-1H-pyrrolo[1,2,3-de]quinoxalin-2(3H)-one.

EXAMPLE VII

6 - ethyl-5-phenyl - 1H - pyrrolo[1,2,3-de]quinoxalin-2(3H)-one (8.3 g., 0.03 mole) is added to a mixture of hexane washed 50% sodium hydride (1.52 g., 0.0316 mole) in anhydrous dimethylformamide (50 ml.) and the mixture is stirred at room temperature until all the solids dissolve. A solution of 3-dimethylaminopropyl chloride (4.02 g., 0.033 mole) in anhydrous dimethylformamide (5 ml.) is added all at once, and stirred at 70-90° C. for one and a half hours. All of the solvent is removed under vacuum and the residue is dissolved in a mixture of methylene chloride-water. The water is extracted once more with methylene chloride, and the methylene chloride washed with water, saturated salt, and dried with sodium sulfate. Concentration under vacuum, gives a tan solid (10 g.), M.P. 108° C. (uncorr.). The solid is crystallized from absolute ethanol, giving white crystals of 6-ethyl-1-(3-dimethylaminopropyl)-5-phenyl - 1H - pyrrolo[1,2,3-de]quinoxalin-2(3H)-one (9.5 g., 88% yield), M.P. 114-116° C. (uncorr.).

Analysis.—Calcd. for C₂₃H₂₇N₃O: C, 76.42; H, 7.53; N, 11.63. Found: C, 76.36; H, 7.51; N, 11.70.

EXAMPLE VIII

When the procedure of Example I is repeated to react pyrrolo[1,2,3-de]quinoxalin-2(3H)-ones with appropriate halide derivatives, the following compounds are afforded:

- 3-(3-dimethylamino)-8,9,10,11-tetrahydro-1H,7H-cyclohepta[4,5]pyrrolo[1,2,3-de]quinoxalin-2(3H)-one, M.P. 104-106° C., 56% yield;
 8,9,10,11-tetrahydro-3-methyl-1H,7H-cyclohepta[4,5]pyrrolo[1,2,3-de]quinoxalin-2(3H)-one, M.P. 113-115° C., 100% yield;
 3-(2-dimethylaminoethyl)-8,9,10,11-tetrahydro-1H,7H-cyclohepta[4,5]pyrrolo[1,2,3-de]quinoxalin-2(3H)-one, M.P. 101.5-103° C., 49% yield;
 2,3,8,9,10,11-hexahydro-2-oxo-1H,7H-cyclohepta[4,5]pyrrolo[1,2,3-de]quinoxaline-3-acetonitrile, M.P. 239-241° C., 67% yield;
 8,9,10,11-tetrahydro-3-phenethyl-1H,7H-cyclohepta[4,5]pyrrolo[1,2,3-de]quinoxalin-2(3H)-one, M.P. 163.5-165° C., 41% yield;

- 6-methyl-1-(2-dimethylaminoethyl)-5-phenyl-1H-pyrrolo[1,2,3-de]quinoxalin-2(3H)-one, M.P. 150-152° C., 68% yield;
 1-(3-dimethylaminopropyl)-5-methyl-6-phenyl-1H-pyrrolo[1,2,3-de]quinoxalin-2(3H)-one, M.P. 140-142.5° C., 84% yield;
 3-(2-dimethylaminoethyl)-7,8,9,10,11,12-hexahydro-1H-cycloocta[4,5]pyrrolo[1,2,3-de]quinoxalin-2(3H)-one, M.P. 112-114° C., 64% yield;
 10 3-(3-dimethylaminopropyl)-8,9-dihydro-1H,7H-cyclopenta[4,5]pyrrolo[1,2,3-de]quinoxalin-2(3H)-one, M.P. 102-103° C., 68% yield;
 5-benzyl-1-(2-dimethylaminoethyl)-6-phenyl-1H-pyrrolo[1,2,3-de]quinoxalin-2(3H)-one, M.P. 152-153° C., 60% yield;
 1-(3-dimethylamino-2-methylpropyl)-6-ethyl-5-phenyl-1H-pyrrolo[1,2,3-de]quinoxalin-2(3H)-one, M.P. 121-123° C., 40% yield;
 1-(3-dimethylamino-1-methylpropyl)-6-ethyl-5-phenyl-1H-pyrrolo[1,2,3-de]quinoxalin-2(3H)-one, M.P. 96.5-98° C., 17% yield;
 1-(2-dimethylaminoethyl)-6-ethyl-5-phenyl-1H-pyrrolo[1,2,3-de]quinoxalin-2(3H)-one, M.P. 154-155.5° C., 76% yield;
 25 1-(3-dimethylaminopropyl)-6-methyl-5-phenyl-1H-pyrrolo[1,2,3-de]quinoxalin-2(3H)-one, M.P. 127.5-129.5° C., 80% yield;
 1-(3-dimethylaminopropyl)-5-phenyl-6-propyl-1H-pyrrolo[1,2,3-de]quinoxalin-2(3H)-one, M.P. 119-121.5° C., 61% yield;
 30 1-(3-dimethylaminopropyl)-6-ethyl-5-methyl-1H-pyrrolo[1,2,3-de]quinoxalin-2(3H)-one, M.P. 88-90.5° C., 67% yield;
 6-ethyl-1-(2-morpholinoethyl)-5-phenyl-1H-pyrrolo[1,2,3-de]quinoxalin-2(3H)-one, M.P. 163.5-165.5° C., 83% yield;
 1-(2-diethylaminoethyl)-6-ethyl-5-phenyl-1H-pyrrolo[1,2,3-de]quinoxalin-2(3H)-one, M.P. 91-92.5° C., 62% yield;
 40 6-ethyl-1-(3-morpholinopropyl)-5-phenyl-1H-pyrrolo[1,2,3-de]quinoxalin-2(3H)-one, M.P. 110-112° C., 67% yield;
 N-[3-(6-ethyl-2,3-dihydro-2-oxo-5-phenyl-1H-pyrrolo[1,2,3-de]quinoxalin-1-yl)propyl]-N-methylformamide, M.P. 124.5-126.5° C., 63% yield;
 45 6-ethyl-5-phenyl-1-[2-(1-pyrrolidinyl)ethyl]-1H-pyrrolo[1,2,3-de]quinoxalin-2(3H)-one, M.P. 160-161.5° C., 84% yield;
 6-ethyl-1-(3-methylaminopropyl)-5-phenyl-1H-pyrrolo[1,2,3-de]quinoxalin-2(3H)-one, M.P. 212-214° C., 30% yield;
 50 6-ethyl-5-phenyl-1-[3-(1-pyrrolidinyl)propyl]-1H-pyrrolo[1,2,3-de]quinoxalin-2(3H)-one, M.P. 135-136° C., 77% yield;
 55 1-(3-dimethylaminopropyl)-5-(p-methoxyphenyl)-6-methyl-1H-pyrrolo[1,2,3-de]quinoxalin-2(3H)-one, M.P. 169.5-171° C., 85% yield;
 5-(p-benzyloxyphenyl)-1-(3-dimethylaminopropyl)-6-methyl-1H-pyrrolo[1,2,3-de]quinoxalin-2(3H)-one, M.P. 138-140° C., 79% yield;
 60 5-(m-chlorophenyl)-1-(3-dimethylaminopropyl)-6-methyl-1H-pyrrolo[1,2,3-de]quinoxalin-2(3H)-one, M.P. 107-109° C., 77% yield;
 65 5-(p-chlorophenyl)-1-(3-dimethylaminopropyl)-6-methyl-1H-pyrrolo[1,2,3-de]quinoxalin-2(3H)-one, M.P. 186-188° C., 71% yield;
 1-(3-dimethylaminopropyl)-5-(p-hydroxyphenyl)-6-methyl-1H-pyrrolo[1,2,3-de]quinoxalin-2(3H)-one, M.P. 172.5-175.5° C., 88% yield;
 70 1-(3-dimethylaminopropyl)-5-phenyl-1H-pyrrolo[1,2,3-de]quinoxalin-2(3H)-one, M.P. 131-132° C., 14% yield; and
 5-(o-chlorophenyl)-1-(3-dimethylaminopropyl)-6-methyl-1H-pyrrolo[1,2,3-de]quinoxalin-2(3H)-one, M.P. 190.5-192.5° C., 61% yield.

EXAMPLE IX

7,8,9,10-tetrahydro - 8 - methyl-1H-pyrido[3',4':4,5]pyrrolo[1,2,3-de]quinoxalin-2(3H)-one (0.06 mole) is added to a mixture of hexane washed 50% sodium hydride (0.0632 mole) in anhydrous dimethylformamide (50 ml.), and the mixture is stirred at room temperature until all the solids dissolve. A solution of 3-dimethylaminopropyl chloride (0.066 mole) in anhydrous dimethylformamide (10 ml.) is added all at once, and stirred at 70-90° C. for two hours. All of the solvent is removed under vacuum and the residue is dissolved in a mixture of methylene chloride-water. The water is extracted once more with methylene chloride, the methylene chloride washed with water, saturated salt, and dried with sodium sulfate. Concentration under vacuum, affords a solid which is crystallized from absolute methanol to afford 7,8,9,10-tetrahydro-8-methyl-1-(3 - dimethylaminopropyl) - 1H - pyrido[3',4':4,5]pyrrolo[1,2,3-de]quinoxalin-2(3H)-one.

In a similar manner, the following compounds are prepared:

8-t-butyl-7,8,9,10-tetrahydro-1-[2-(1-pyrrolidinyl)ethyl]-1H-pyrazino[3,2,1-*jk*]carbazol-2(3H)-one;
1-ethyl-2,3-dihydro-2-oxo-5-phenyl-1H-pyrrolo[1,2,3-de]quinoxaline-6-acetic acid;
1-[3-(1-aziridinyl)propyl]-8,9-dihydro-1H,7H-cyclopenta[4,5]pyrrolo[1,2,3-de]quinoxalin-2(3H)-one;
1-benzyl-7,8-dihydro-1H-benzo[*a*]pyrazino[3,2,1-*jk*]carbazol-2(3H)-one;
7,8,9,10,11,12,13,14,15,16-decahydro-1-(2-dimethylaminoethyl)-1H-cyclododeca[4,5]pyrrolo[1,2,3-de]quinoxalin-2(3H)-one;
2,3-dihydro-1,5-dimethyl-2-oxo-1H-pyrrolo[1,2,3-de]quinoxaline-6-carboxylic acid, ethyl ester;
6-(2-hydroxyethyl)-5-(*p*-methoxyphenyl)-1-phenpentyl-

- 5 1-(2-[1-(*p*-iodophenyl)piperazinyl]ethyl)-8-(2-naphthyl)-1H-pyrrolo[1,2,3-de]quinoxalin-2(3H)-one;
1-(4-[1-(*p*-fluorophenyl)piperazinyl]butyl)-8-(*p*-methoxyphenyl)-1H-pyrrolo[1,2,3-de]quinoxalin-2(3H)-one;
10 1-ethyl-8-(*p*-propoxyphenyl)-1H-pyrrolo[1,2,3-de]quinoxalin-2(3H)-one;
1-(2-cyanoethyl)-8-phenethoxy-1H-pyrrolo[1,2,3-de]quinoxalin-2(3H)-one;
1-methyl-9-dipropylamino-1H-pyrrolo[1,2,3-de]quinoxalin-2(3H)-one;
1-benzyl-8-(*p*-fluorophenyl)-1H-pyrrolo[1,2,3-de]quinoxalin-2(3H)-one; and
15 1-ethyl-8-(*N*-methyl-*N'*-propylamino)-1H-pyrrolo[1,2,3-de]quinoxalin-2(3H)-one.

EXAMPLE X

20 When the procedure of Examples I-III is repeated to react pyrrolo[1,2,3-de]quinoxalin-2(3H)-ones with appropriate halide derivatives, compounds having the following formula are obtained:

25

30

35

wherein R₁, R₂, R₃, R₄ and R₅ are defined as follows:

R ₁	R ₂	R ₃	R ₄	R ₅
Hydrogen	8-cyano	<i>p</i> -Tolyl	Propyl	Propyl
8-chloro	9-chloro	Carboxy	<i>p</i> -Bromophenyl	4-morpholinobutyl
8-trifluoromethyl	Hydrogen	Hydrogen	Carbomethoxy	2-cyanoethyl
7-ethoxy	8-amino	Carbamyl	<i>p</i> -Hydroxyphenyl	3-diethylaminopropyl
9-bromo	8-carboxy	<i>p</i> -Ethylphenyl	Hydrogen	3-(<i>N</i> -acetyl- <i>N'</i> -ethylamino)propyl
8-ethyl	Hydrogen	Hydrogen	<i>p</i> -Methoxyphenyl	4-(<i>N</i> -methyl- <i>N'</i> -propionylamino)butyl
8-fluoro	9-sulfamyl	do	Butyryl	4-(1-aziridinyl)butyl
8-nitro	9-phenyl	<i>p</i> -Iodophenyl	Hydrogen	4-cyanobutyl
8-carbamyl	9-methylthio	Hydrogen	Valeryl	3-(1-pyrrolidinyl)propyl
7-butyl	Hydrogen	do	Carbethoxy	2-(1-azetidinyl)ethyl
8-ethylthio	9-ido	Phenpropyl	Hydrogen	5-(1-azepinyl)pentyl
8-methoxy	9-methoxy	Hydrogen	Dimethylaminooethyl	4-dibutylaminobutyl
8- <i>p</i> -chlorophenyl	Hydrogen	do	Hydrogen	2-dimethylaminooethyl
8-morpholino	do	do	2-pyridyl	3-(1-azetidinyl)propyl
8-methylsulfonyl	9-propoxy	do	2-naphthyl	3-(1-pyrrolidinyl)propyl
Hydrogen	9-acetamido	do	Cyano	2-(1-azepinyl)ethyl
8-ethylsulfonyl	9-acetyl	do	<i>m</i> -Fluorophenyl	4-propylaminobutyl
7-carbomethoxy	8-benzyl	do	Naphthyl	4-(1-pyrrolidinyl)butyl
8-dimethylamino	Hydrogen	do	2-furyl	2-methylaminooethyl
8-pyridyl	9-butylthio	Diethylaminopropyl	Hydrogen	2-(1-methylpiperazinyl)ethyl
Hydrogen	9-benzylxylo	Hydrogen	do	3-(1-phenylpiperazinyl)propyl
8-carbethoxy	9- <i>p</i> -bromophenyl	<i>p</i> -Butoxyphenyl	Phenethyl	3-ethylaminopropyl
7-propionyl	Hydrogen	Hydrogen	Hydrogen	Benzyl
8-phenethyl	do	do	Carbpropoxy	2-(1-aziridinyl)ethyl
8-propionamido	do	do		4-(1-azepinyl)butyl

1H-pyrrolo[1,2,3-de]quinoxalin-2(3H)-one, acetate;
1-butyl-5-(*p*-methoxyphenyl)-6-methyl-1H-pyrrolo[1,2,3-de]quinoxalin-2(3H)-one;
13-chloro-7,8,9,10-tetrahydro-1-[3-(1-methylpiperazinyl)propyl]-8-propyl-1H-pyrido[3',4':4,5]pyrrolo[1,2,3-de]quinoxalin-2(3H)-one;
1-(2-[1-(*p*-chlorophenyl)piperazinyl]ethyl)-7,8,9,10-tetrahydro-8,14-dimethyl-1H-pyrido[3',4':4,5]pyrrolo[1,2,3-de]quinoxalin-2(3H)-one;
1-(3-[1-(*m*-bromophenyl)piperazinyl]propyl)-6-(3-hydroxypropyl)-8-phenethyl-1H-pyrrolo[1,2,3-de]quinoxalin-2(3H)-one, propionate;
8-benzyl-1-[4-(1-benzylpiperazinyl)butyl]-1H-pyrrolo[1,2,3-de]quinoxalin-2(3H)-one;
8-(2-furyl)-1-[3-(1-phenethylpiperazinyl)propyl]-1H-pyrrolo[1,2,3-de]quinoxalin-2(3H)-one;
9-diethylamino-1-methyl-1H-pyrrolo[1,2,3-de]quinoxalin-2(3H)-one;

60 What is claimed is:
1. A compound selected from the group consisting of those having the formula:

65

70 wherein

R₁ is lower alkyl having from one to seven carbon atoms;
R₂ and R₃ when taken separately are hydrogen, and
R₂ and R₃ when taken together with the two carbon atoms to which they are attached complete a benzo ring.

11

2. A compound as described in claim 1 which is: 8-
tert-butyl - 7,8,9,10 - tetrahydro - 1H - pyrazino[3,2,1-*jk*]carbazol-2(3H)-one.

3. A compound as described in claim 1 which is: 7,8-
dihydro-1H-benzo[*a*]pyrazino[3,2,1-*jk*]carbazol - 2(3H)-one.
